UNITED STATES PATENT OFFICE.

EDWARD O. STARKA, OF CHICAGO, ILLINOIS.

TACK-FEEDING MACHINE.

1,408,482.

Specification of Letters Patent.

Patented Mar. 7, 1922.

Application filed June 28, 1920. Serial No. 392,369.

To all whom it may concern:

Be it known that I, EDWARD O. STARKA, a citizen of the United States, and a resident of the city of Chicago, county of Cook, and 5 State of Illinois, have invented certain new and useful Improvements in Tack-Feeding Machines, of which the following is a specification.

My invention relates to new and useful 10 improvements in tack feeding machines, and has for its object the provision of a machine of this class which will be simple and durable in structure, capable of economical manufacture and highly efficient in use. 15 Another object is the provision of means for oscillating the guide tube while in use. Another object is the provision of means for feeding the tack blank a pre-determined distance upon each oscillation of the guide tube. 20 Other objects will appear hereinafter.

The invention consists in the combinations and arrangements of parts hereinafter described and claimed.

The invention will be best understood by 25 reference to the accompanying drawings forming a part of this specification, and in which,

Fig. 1, is a side elevational view of the invention,

Fig. 2, a top plan view of the invention, 30 Fig. 3, a sectional longitudinal vertical sectional view of the invention,

Fig. 4, a front elevational view of the invention,

Fig. 5, a rear elevational view of the invention, 35 Fig. 6, a fragmentary view showing in detail the feed actuating means,

Fig. 7, a face view of a ratchet employed 40 in the construction,

Fig. 8, a fragmentary elevational view of a modified form of the feed actuating mechanism,

Fig. 9, a sectional view taken on substantially line 9—9 of Fig. 1, 45

Fig. 10, a sectional view taken on substantially line 10—10 of Fig. 2, and

Fig. 11, a perspective view of the stirrup used for oscillating the guide tube.

The preferred form of construction comprises a guide tube 12 which is provided adjacent its rear end with a circumferential rib 13. The tube 12 is provided adjacent its forward end with a similar circumferential 50 rib 14. A standard 15 is provided, which is secured to the floor or other supporting

frame, said standard being provided at its upper end with a block 16 provided with a groove 17 in which the rib 13 is adapted to engage, the member 15 thereby serving to support the tube 12 at its rearward end, the forward end of the tube 12 resting upon the table 20' which is usually present in tack machines. Adjacent the forward end of the tube 12 is provided a standard 17' which passes adjacent one side of the tube 12 and is provided at its upper end with an arcuate spring 19 which is adapted to engage the upper surface of the tube 12. As the tube 12 oscillates, the forward end thereof, which is tapered, engages the table 20' and raises upwardly, the spring 19 serving to resist the upward movement of this end of the tube. Upon the complete oscillation, the spring 19 restores the tube to its operating 75 position upon the table 20'. The forward end of the tube 12 is provided with a tongue 20 which projects beyond the main body thereof, the tongue 20 being formed centrally longitudinally of the tube 12 so as to engage the strip of metal which passes through the slot formed longitudinally of the tube 12. As shown in Fig. 1, the rearward end of the tube 12 is formed flaring, as at 22, so that an insertion of the metal 80 blank 23 from which the tube is to be made may be readily had in the slot 21 formed in the tube. Adjacent the rearward end of the tube is positioned a circumferential rib 24 which is provided with teeth, the member 24 being rigidly attached to the tube 12. Embracing the tube 12 is a U-shaped member or stirrup 25, the legs of which are joined together by an arcuate bar 26 which is adapted to mesh with the teeth formed on the member 24. Secured to the bight of the member 25, centrally thereof, is one arm 27 of a bell crank, the opposite arm 28 of which is secured to the usual reciprocating rod 85 ordinarily operated by the tack machine to oscillate the guide tube. The bell crank is pivoted upon the standard or support 30 secured to the table or floor, as the case may be. It is evident that upon reciprocation of the rod 29 the arm 27 is caused to rock transversely of the tube 12, thereby reciprocating the member 25 transversely of the tube 12. As the member 25 reciprocates, the teeth on the member 26, engaging with the teeth on the member 24, causes the tube 12 to oscillate, thereby presenting, alternately, the opposite sides of the strip 23 in engagement 100

105

110

with the table 20' so as to provide for the proper angle of the cut made by the knife of the tack machine on the strip 23. Mounted upon the member 12, adjacent its rearward end, is a housing 31 through which projects, adjacent its upper end, a shaft 32. The portion of the housing through which the shaft 32 projects is provided at its inner side with a shoulder 33 having an opening therethrough of greater diameter than the diameter of the shaft. Positioned within the housing, intermediate the wall thereof and the tube 12, at opposite sides of said tube, are bearings 34, in which the shaft 32 is journaled. Mounted in a slot 35' formed in the tube 12, and rigidly attached to the shaft 32, is a roller 35. Adjacent the lower end of the housing 31 a shaft 36 is projected therethrough, said shaft 36 being 10 journaled in bearings 37 similarly formed and similarly positioned to the bearings 34. The housing 31 is provided on its inner surface at the point where the shaft 36 passes through, with a shoulder similarly constructed to the shoulder 33. Mounted in a slot formed in the tube 12 and positioned upon the shaft 36 is a roller 38 which is designed to co-operate with the roller 35 for engaging and feeding forward the tack blank 23 inserted in the slot 21. Rigidly attached to the shaft 32, exterior to the housing 31, is a gear wheel 39, which is adapted to mesh with a gear wheel 40 which is rigidly attached to the shaft 36 and positioned exteriorly of the housing 31. To the opposite end of the shaft 36, exteriorly of the housing 31, is rigidly attached a bevel gear 41. Owing to the fact that the opening through the housing is larger than the shafts 32 and 36, it is evident that the rollers 35 and 38 are movable relatively to each other. Provided upon the upper surface of the housing 31 are arranged spring members 42 and 43, which are adapted to engage 15 the upper surface of the bearings in which the shafts 32 and 36 are mounted so as to press the rollers 35 and 38 into close relation with each other, suitable slots being provided in the upper wall of the housing 31 for passage of the bearings therethrough upon spreading apart of the rollers 35 and 38. Similarly, the lower wall of the housing 31 is provided with slots through which the bearings in which shaft 36 is mounted 20 may project, and similar springs 44 and 45 are provided for resisting the outward movement of the bearings in which the shaft 36 is mounted, so as to maintain the rollers 35 and 38 in close relation to each other. The purpose of movably mounting these rollers in the manner indicated, is to provide for a spreading apart of the same should any inequalities in the material 25 be present as the same passes through the 60 rollers. Rigidly mounted upon the shaft 36, 65 exterior of the housing 31, is a bevel gear 41 which is adapted to mesh with a bevel gear 46 which is rigidly attached to one end of a shaft 47 journaled in bearings 48 and 49 mounted upon the housing 31 and 31', the 70 housing 31' being similarly arranged and similarly constructed to the housing 31. To the opposite end of the shaft 47 is rigidly attached a bevel gear 50, which is adapted to mesh with a bevel gear 51 which is rigidly 75 attached to a shaft 52 projecting through the housing 31 and is journaled in bearings similar to the shaft 36. The shaft 52 is likewise provided with a roller 54 similar to the rollers already described. The roller 54 is 80 designed for co-operation with a roller 53 mounted upon a shaft 53' which projects through the housing 31' and is journaled in bearings such as are present in the housing 31. Similar springs 56 and 55 are provided 85 upon the lower and upper walls, respectively, of the housing 31' for the same purpose as the springs already described as attached to the housing 31. Mounted upon the shaft 53', exterior of the housing 31, is a pinion 90 57 adapted to mesh with a pinion 58 which is rigidly attached to the shaft 52. Mounted upon the opposite end of the shaft 52 is a gear wheel 59, which is adapted to mesh with a gear 60 which is rigidly attached to 95 a ratchet wheel 61. Said ratchet wheel is loosely mounted upon a shaft 62 which projects through the housing 31'. Mounted upon the platform or table to which the standard 15 is secured, are suitable posts 63 and 64, said posts being positioned at opposite sides of the tube 12. Loosely mounted upon the shaft 62, exteriorly of the ratchet wheel 61, is an arm 65 bearing at opposite ends oppositely directed pawls 66 and 67 100 which are adapted to engage the teeth on the ratchet wheel 61. Projecting outwardly from the member 65, adjacent its opposite ends, are suitable stops 68 and 69 so positioned that upon oscillation of the tube 12, 105 one of the stops 69 engages the upright 64 while the other stop 68 engages the upright 63. In operation, upon reciprocating the rod 29, oscillation of the tube takes place, as 110 already explained. When oscillation takes place while the machine is in the position shown in Fig. 4, the outwardly extending post or stop 68 will engage the member 63 and cause a movement of the arm 65 relatively to the shaft 62. This will cause a rotation of the ratchet wheel 61 for a pre-determined distance, depending upon the distance the tube 12 oscillates after the member 68 has engaged the post. This will 115 cause a rotation of the gear 60 and a consequent rotation of the rollers is brought about. In this manner, the tack blank is fed the necessary distance for cutting off individual tacks at each operation. The set 120

of rollers contained within the housing 31 are merely auxiliary rollers for the purpose of feeding an auxiliary strip of metal so that the two strips of metal may be contained within the tube at the same time. Rigidly attached to the shaft 62 is an arm 71, to one end of which is attached one end of a spiral spring 73, the opposite end being attached adjacent the end of the arm 65 to 10 which the pawl 66 is secured. To the opposite end of the member 71 is attached one end of a spiral spring 72, the opposite end of which is attached to the arm 65 adjacent the end to which the pawl 67 is secured. The purpose of the springs 73 and 15 72 is to return the arm 65 to its former position relatively to the shaft 62 after each engagement with the stops 63 or 64.

As shown in Fig. 7, there is mounted upon 20 the member 71 and preferably made integral therewith, a stop 72', which is adapted to limit the backward movement of the arm 65 in response to the strain of the spring 72. Mounted upon the arm 71 is a similar stop 25 73', which is adapted to limit the backward movement of the arm 65 in response to the strain of the spring 73.

In Fig. 8, I have shown a modified form 30 of the actuating device of the ratchet wheel, in which the arm 65 and the stops 63 and 64 and the necessary co-operating parts are dispensed with. Mounted upon a pedestal 74 is an arm 75, which extends to one side 35 of the tube 12 and is provided at its end with a tubular portion 76 in which is slidably positioned a stem 78 having a pawl 79 at one end thereof, adapted to engage the teeth of the ratchet wheel 61. The member 76 is provided adjacent its upper end with 40 a recess in which is seated a spiral spring which is sleeved upon the upper end of the member 78. One end of the spiral spring 82 is adapted to engage the base of the recess 80, whereas the other end is adapted 45 to engage the under surface of a cap 81 which is secured to the stem 78. The opposite end of the stem 78 is provided with a collar 83, which limits its upward movement relatively to the member 76. The construction 50 is such that upon oscillating the tube 12, the ratchet 61 is brought into engagement with the pawl 79 and a consequent rotating of the ratchet 61 results, the spiral spring providing for slight movement of the member 78 within the tubular member 76 so as to absorb the shock naturally incident 55 to the sudden contacting of the teeth on the ratchet wheel with the pawl 79. Projecting from the pedestal 74 and extending to the 60 opposite side of the member 12 is a stem similarly constructed and similarly positioned to the stem 78. In Fig. 2 I have shown guide members 84 and 85 which are usually connected with a tack machine. 65 The guide members 85 and 84 are provided,

respectively, with inwardly turned portions 86 and 87 which are adapted to engage the tack blank 23 at opposite sides thereof, so as to retain the same rigid while the knife is making the cutting stroke. These members 70 84 and 85 are usually formed of some spring metal, and are merely shown here for the purpose of illustration, the same forming no part of this invention.

While I have illustrated and described the 75 preferred form of construction for carrying my invention into effect, this is capable of variation and modification without departing from the spirit of the invention. I, therefore, do not wish to be limited to the 80 precise details of construction set forth, but desire to avail myself of such variations and modifications as come within the scope of the appended claims.

Having described my invention, what I 85 claim as new and desire to secure by Letters Patent is:—

1. A tack feeding machine comprising an oscillatory guide member loosely mounted on supports; and a stirrup embracing said 90 guide member for retaining said guide member on said supports while imparting oscillatory movement thereto, substantially as described.

2. A tack feeding machine comprising an 95 oscillatory guide member loosely mounted on supports; teeth arranged circumferentially on said guide member; a rack bar adapted to mesh with said teeth; a stirrup embracing said guide member and connected 100 with the opposite ends of said rack for retaining said guide member on said supports while imparting oscillatory movement thereto; and means for reciprocating said stirrup transversely of said guide member 105 for oscillating the same, substantially as described.

3. A tack feeding machine comprising an oscillatory guide member loosely mounted 110 on supports; teeth arranged circumferentially on said guide member; a rack bar adapted to mesh with said teeth; a stirrup embracing said guide member and connected with the opposite ends of said rack for retaining said guide member on said supports while imparting oscillatory movement thereto; and a bell crank lever mounted on 115 a support adjacent said stirrup and having one end connected intermediate the ends of said stirrup; and means for actuating said bell crank lever for reciprocating said stirrup transversely of said guide member for oscillating the same, substantially as described.

4. A tack feeding machine comprising an 120 oscillatory guide member having a passage formed therein; means mounted on said guide member for feeding a tack blank through said passage; means for oscillating 125 said guide member; stop members mounted 130

at opposite sides of said guide member; and means actuated by said stop members upon each oscillation of said guide member for actuating said feeding means, substantially as described.

5. A tack feeding machine comprising an oscillatory guide member having a passage formed therein; teeth arranged circumferentially on said guide member; a rack bar 10 adapted to mesh with said teeth; a stirrup connected to opposite ends of said rack bar and embracing said guide member; and means connecting said stirrup with a reciprocating rod for reciprocating said stirrup transversely of said guide member upon reciprocation of said reciprocating rod, substantially as described.

6. A tack feeding machine comprising an oscillatory guide member having a passage 20 formed therein; feeding means mounted in said guide member for feeding a tack blank through said passage; a ratchet wheel mounted on said guide member for actuating said feeding means, and means operable 25 by impact for actuating said ratchet wheel upon each oscillation of said guide member, substantially as described.

7. A tack feeding machine comprising an oscillatory guide member having a passage 30 formed therein; means for oscillating said guide member; means mounted on said guide member for feeding a tack blank through said passage; stops positioned at opposite sides of said guide member; a 35 ratchet wheel mounted on said guide member; means actuated upon the rotation of said ratchet wheel for actuating said feeding means; and means actuated by said stop members upon each oscillation of said guide 40 member for rotating said ratchet wheel, substantially as described.

8. A tack feeding machine comprising an oscillatory guide member having a passage formed therein; means for oscillating said 45 guide member; a plurality of feeding means mounted on said guide member for feeding tack blanks through said passage; a ratchet wheel mounted on said guide member; means for actuating said feeding means 50 synchronously upon the rotation of said ratchet wheel; stop members positioned at opposite sides of said guide member; and means adapted to engage said stop members upon each oscillation of said guide member 55 for rotating said ratchet wheel, substantially as described.

9. A tack feeding machine comprising an oscillatory guide member having a passage formed therein; means for oscillating said 60 guide member; feeding means mounted on said guide member for feeding a tack blank through said passage; a ratchet wheel mounted on said guide member; means actuated by said ratchet wheel for actuating 65 said feeding means upon the rotation of

said ratchet wheel; stop members mounted at opposite sides of said guide member; an arm pivotally mounted on said guide member; pawls mounted at opposite ends of said guide member and adapted to engage the 70 teeth of said ratchet wheel; and additional stop members mounted on said arm adapted for engagement with said first mentioned stop members upon each oscillation of said guide member for swinging said arm pivot- 75 ally for rotating said ratchet wheel, substantially as described.

10. A tack feeding machine comprising an oscillatory guide member; means mounted on said guide member for feeding a tack 80 blank therethrough; means for oscillating said guide member; stop members mounted adjacent said guide members; and means actuated by said stop members upon each oscillation of said guide member for actuating 85 said feeding means, substantially as described.

11. A tack feeding machine comprising an oscillatory guide member; means for feeding a tack blank through said guide 90 member; and means on said guide member for actuating said feeding means by contact with an immovable member during oscillation of said guide member, substantially as described.

95

12. A tack feeding machine comprising an oscillatory guide member having a slot therein; means for feeding a tack blank through said slot; means for oscillating said guide member; and means on said 100 guide member for actuating said feeding means by contact with an immovable member during oscillation thereof, substantially as described.

13. A tack feeding machine comprising an oscillatory guide member having a passage formed therein; means for oscillating said guide member; supports for said guide member; and a resilient member on said supports for retaining said guide member 110 in operative position, substantially as described.

14. A tack feeding machine comprising an oscillatory guide member having a passage formed therein; a plurality of feeding means mounted in said guide member for feeding a tack blank through said passage; means for oscillating said guide member; stop members mounted on the opposite sides of said guide member; and means actuated by said stop members upon each oscillation thereof for actuating said feeding means synchronously, substantially as described.

115

15. A tack feeding machine comprising an oscillatory guide member having a passage formed therein; a housing mounted on said guide member; shafts loosely mounted in said housing to permit play therein; separated bearing members engaging said 120 125 130

shafts; a pair of co-operating rollers mounted on said shafts for feeding material through said passage, said rollers being movable relatively to each other; and resilient means engaging said bearings for maintaining said rollers in normally fixed relation to each other, substantially as described.

16. A tack feeding machine comprising
10 an oscillatory guide member having a passage formed therein; means for oscillating said guide member; feeding means mounted on said guide member for feeding a tack blank through said passage; a ratchet wheel
15 mounted on said guide member; means for

imparting a step by step movement to said ratchet wheel upon each oscillation of said guide member; a pinion attached to said ratchet wheel; and a gear attached to said feeding means and meshing with said 20 pinion to impart a step by step movement to said feeding means.

In testimony whereof I have signed my name to this specification in the presence of two subscribing witnesses.

EDWARD O. STARKA.
